UNITED STATES PATENT OFFICE

154,108

DESIGN FOR AN ELECTRIC DRIVEN LAWN MOWER

Albert Edwin Emmons, Lockport, N. Y., assignor
to Rumsey Products, Inc., Seneca Falls, N. Y.,
a corporation of New York

Application December 18, 1946, Serial No. 135,590

Term of patent 14 years

(Cl. D40—1)

To all whom it may concern:

Be it known that I, Albert E. Emmons, a citizen of the United States, residing at Lockport, in the county of Niagara and State of New York, have invented a new, original, and ornamental Design for an Electric Driven Lawnmower, of which the following is a specification, reference being had to the accompanying drawing, forming part thereof.

Fig. 1 is a front perspective view of an electric driven lawnmower showing my new design; and

Fig. 2 is a rear perspective view thereof, the handle and electric cord being omitted for convenience in illustration.

I claim:

The ornamental design for an electric driven lawnmower, substantially as shown.

ALBERT EDWIN EMMONS.
